UNITED STATES PATENT OFFICE

THORE R. E. RUNDQVIST, OF CLAREMONT, NEW HAMPSHIRE, ASSIGNOR TO SULLIVAN MACHINERY COMPANY, A CORPORATION OF MASSACHUSETTS

ROCK-DRILLING MECHANISM

Application filed October 12, 1923. Serial No. 668,198.

My invention relates to rock drilling mechanisms.

An object of my invention is to provide an improved rock drilling mechanism and more particularly an improved rock drilling mechanism of the pneumatically fed type. Another object of my invention is to provide an improved rock drilling mechanism of the fluid pressure percussive type having improved fluid pressure operated feeding mechanism and improved controlling mechanism therefor. A further object of my invention is to provide an improved fluid pressure percussive rock drilling mechanism of the pneumatically fed type having improved controlling mechanism for the drilling motor and the feeding means. A still further object of my invention is to provide improved controlling means for a fluid pressure operated rock drilling mechanism of the self feeding type whereby the feeding means and the drilling motor may be simultaneously controlled by an operator with the use of but one hand. These and other objects and advantages of my improved mechanism will hereinafter more fully appear.

In the accompanying drawings I have shown for purposes of illustration three forms which my invention may assume in practice.

In these drawings,—

Fig. 1 is an elevational view, partially broken away, showing a drilling mechanism embodying my improved mechanism.

Fig. 2 is a transverse sectional view taken substantially on line 2—2 of Fig. 1 with the operating handle shown swung into the plane of the section line.

Fig. 3 is a view showing one position of the throttle valve and illustrating sections taken substantially on lines a—a and b—b of Fig. 2.

Fig. 4 is a similar view as shown in Fig. 3 with the valve in a different position.

Fig. 5 is a detail sectional view of the feed controlling valve.

Fig. 6 is a sectional view corresponding to that shown in Fig. 2 showing a modified form of construction.

Fig. 7 is a sectional view showing a further

modified form of construction corresponding to that shown in Fig. 2.

In the first illustrative form of my invention I have shown a rock drilling mechanism of the so-called "stoper" type generally designated 1 which comprises a drilling motor 2 of the fluid pressure percussive type adapted to percussively actuate a drill steel 3 carried in the front end of the drilling motor, and a feeding means, generally designated 4, of the fluid pressure operated type. This feeding means comprises a feed cylinder 5 having a feed piston 6 reciprocable therein. The feed piston is provided with a piston rod 7 and an abutment engaging point 8 adapted to engage a stationary extraneous abutment during the drilling operation. As the drilling motor, acting through the drill steel 3, deepens the hole the cylinder 5 moves upward relative to the piston 6. The drilling motor parts and the feeding mechanism are suitably held in assembled relation by means of side rods 9, in a well known manner. Suitably secured in a head block 10 of the drilling motor, which is disposed intermediate the motor and the feeding means, is a laterally projecting handle 11 which is used to support the drilling mechanism and to rotate the drill steel if automatic rotation is not present.

Disposed in a conical bore 12 in a boss 13 formed on the head block 10 is a throttle valve 14 of conical shape. This valve 14 is hollowed out, as at 15, and this hollowed out portion communicates with the fluid pressure supply which is admitted to the throttle valve by means of a swiveled hose connection 16 from any suitable source. Suitably secured to a conical portion 17 formed integral with the valve 14, herein by a bolt connection 18, is an operating handle, generally designated 19, which incorporates improved feed controlling mechanism hereinafter more fully described. A dowel pin 18' engages a flattened portion formed on the conical portion 17 thereby positioning the handle. Traversing the wall of the throttle valve is a port 20 which is adapted to communicate with a passage 21 through which port fluid is admitted to the drilling motor 2. Ex-

tending parallel with the axis of the throttle valve is a passage 22 which communicates, under the control of a feed control valve generally designated 23 of improved form, 5 with the lower end of a bore or chamber 24 formed coaxially within the handle. Communicating with this chamber is a passage 25 disposed parallel with the passage 22, which in turn is adapted to communicate 10 by means of a circumferentially extending groove 26, with a port 27 leading to the interior of the feed cylinder 5. It will herein be noted that usual means is provided for venting the interior of the feed cylinder to 15 atmosphere when the throttle valve is in its closed position (see Fig. 3) and such means comprises a groove 26' in the valve adapted to connect a vent 27' in the boss 13 with the feed port 27. Furthermore, the bore or 20 chamber 24 has a valve stem or pin 28 reciprocably mounted therein on which the valve 23 is formed. This valve is provided with a conical head 29 which is adapted to register with a conical seat 29' and is laterally cut away or 25 slotted as at 30 at a plurality of diametrically opposite points to permit a sensitive graduation of the feed and to prevent jumping of the drill caused by a sudden admission of fluid pressure to the feed cylinder. The valve 30 stem 28 is provided with a collar 31 which is adapted to be engaged by a slide sleeve 32 disposed in an enlarged bore 33 which forms a continuation of the bore 24. This sleeve 32 has an operating member or push 35 button 34 suitably secured thereto as at 35, herein by the peening or heading over of the solid portion formed on the outer extremity of the sleeve 32. This push button is provided with a flanged cylindrical depending portion 36 which has a sliding fit with the outer periphery of the handle 19 thereby preventing 40 foreign matter from entering the working parts of the valve. The sleeve 32 is provided with a slot 37 which engages a pin 45 suitably secured within the handle 19, thereby preventing a derangement of the parts. The upper end of the stem 28 is slidably mounted in a cap member 39 which is disposed in the bore of the sleeve 32. Fluid 50 pressure is adapted to be admitted to a bore 40 formed in this cap member by way of a small passage 41 arranged coaxially through the valve stem and which communicates with the bore or chamber 24, the fluid pressure acting on the upper end of the valve stem which is of a slightly smaller area than the lower end of the valve stem, thereby holding the valve in its wide open position, the cap member 39 engaging with the pin 38 at this time. 55 These areas are so proportioned as to maintain a constant pressure tending to hold the valve open at all times and thereby cause the valve to be operated more easily as distinguished from a spring in which the necessary 60 force to operate increases as the spring is

compressed. The bore of the sleeve 32 is vented to the atmosphere by way of a port 42 and grooves 42', thereby preventing a pressure to build up therein. The throttle valve handle 19 is provided with a laterally projecting handle portion 43 which is adapted to be grasped by the operator at certain times during the drilling operation. It will be noted that if this handle portion were not present the operator's hand might possibly 75 slip from the handle 19 when simultaneously rotating the valve 14 and reciprocating the valve 23. It will be further noted that this handle portion 43 protects the hand of the operator during the drilling operation. 80

In the operation of this form of my invention, after the drilling mechanism has been arranged at the desired angle with the point 8 disposed against an abutment a suitable distance from the working face with the operator grasping the supporting handle 11 at this time, the throttle valve handle 19 may be manipulated, bringing the groove 26 in communication with the port 27 leading to the feed cylinder. Simultaneously the push button 34 is pressed downwardly by means of a finger or thumb, graduating the amount of pressure fluid admitted to the feed as desired. The valve 14 is then further rotated, bringing the port 20 (see Fig. 4) 90 in communication with the passage 21 leading to the drilling motor, thereby percussively actuating the drill steel 3 and "spotting" the hole. After the hole has been "spotted" the feed control valve 23 is gradually opened until a full feed is obtained, the pressure acting on the inner end of the valve stem and holding it in this position. If a seam or soft spot is encountered, causing the drill to jump forward, the operator may quickly 10 press the push button 34 downwardly, seating the valve 23 and consequently retarding the feed thereby preventing the possibility of a stuck drill steel. 10

In the form of my invention shown in Fig. 6 I have shown a device substantially similar to that shown in Figs. 1 to 5 except that the feed control valve and balancing mechanism is arranged coaxially with respect to the valve 14 in a bore 45 which communicates with the hollow chamber 15 by means of a small passage 46. Opening laterally from the chamber or bore 45 is a port 47 communicating with the groove 26 which is adapted to connect the port 27 leading to the feed cylinder with the fluid pressure supply. Arranged within a bore 48 formed in the handle 19 is a lever 49 pivoted at 50 intermediate its ends on the handle. This lever is bifurcated at 51 at its inner end and engages a collar 52 formed on a sleeve 53 corresponding to the sleeve 32. The opposite end of this lever is engaged by the sides of a slot 54 formed in an operating member or push button 55 which is adapted to be recip- 12

located in a plane parallel with the plane of the valve 23 in a grasping portion 56 of the handle 19. A packing 57 is inserted in a groove 58 encircling the push button for preventing the entrance of foreign matter to the working parts.

In the operation of this form of my invention, it will be understood that when the drilling motor is running at full speed and the feed is full on, the feed control valve 23 is held wide open by means of the fluid pressure acting on the end of the valve stem 28. If a soft spot or seam is encountered the push button 55 is moved to the left, swinging the lever 49 about its pivot and consequently seating the valve 23 and retarding the feed. It is clearly apparent that the throttle valve may be rotated and the feed valve 23 reciprocated simultaneously by but one hand of the operator.

In the form of my invention shown in Fig. 7, it will be noted that the feed control valve 23 comprises a plurality of spaced heads 60 and 61 of differential areas reciprocable in a bore 62 of stepped diameters formed in a member 63 suitably secured to the throttle valve 14, the head 60 being adapted to be seated on a seat 64. The lower end of the bore 62 is vented to the atmosphere by way of a small port 65. Suitably connected to the head 60, as at 66, is a flexible operating member or shaft 67 which is preferably in the form of a spring having contacting coils and which is possessed of considerable stiffness and yet has the requisite flexibility desired, thereby permitting operation of the valve even if the handle 19 is accidentally bent out of alignment with the bore 62. This member 67 is provided at its outer end with an operating member or push button 68 similar to the push button 34. A pin and slot connection 69 prevents a derangement of the working parts. It will also be understood that the handle 19 is herein also preferably provided with an upstanding projection of the type of the members 43, 56.

In the operation of this form of my invention the fluid pressure acting on the larger area of the head 60 holds the valve 23 in its wide open position, the operation of the throttle valve 14 being substantially identical to that stated above. If a soft spot or seam is encountered during drilling the push button 68 may be pressed downwardly seating the head 60 and consequently retarding the feed.

As a result of my improvement it is obvious that the operator may manipulate the feed control valve while rotating the throttle valve without removing his hand from the throttle valve control handle. It will further be noted that due to the balanced condition of the feed control valve great ease of operation is obtained, the pressure tending to hold the valve open being the same at all times and that as a result of this arrange-

ment including the throttle valve handle and the feed control push button, these elements may be simultaneously operated by an operator while using but one hand and without difficulty, the projection formed on the handle presenting a suitable support for the hand as the handle is turned or while the push button is freely operated. It will still further be noted that a simple compact structure is obtained which may easily be adapted to a drill of standard form with the minimum of change.

While I have in this application specifically described three forms which my invention may assume in practice, it will be understood that these forms of the same are shown for purposes of illustration and that the invention may be modified and embodied in various other forms without departing from its spirit or the scope of the appended claims.

What I claim as new and desire to secure by Letters Patent is:

1. In a drilling mechanism, a drilling motor and feeding means therefor comprising a pneumatic feed cylinder and piston, a main valve for controlling the fluid pressure supply to said motor and said feeding means, an operating member for said main valve, a valve disposed within said operating member for controlling said feeding means at will, means acted on by fluid pressure for holding said last mentioned valve in wide open position, and means acted on by fluid pressure for resisting said last mentioned means.

2. In a drilling mechanism, a drilling motor and pneumatic feeding means therefor, a main valve for controlling said motor and said feeding means including a plurality of parallel passages extending longitudinally thereof and having a valve stem projecting therefrom, an operating member secured to the stem of said valve, and means carried by said operating member for controlling the communication between said passages.

3. In a drilling mechanism, a drilling motor and pneumatic feeding means therefor, a main controlling valve therefor, an operating handle for said valve extending laterally therefrom, and supplemental means for controlling said feeding means including an operating member carried on the end of said main valve operating handle.

4. In a drilling mechanism, a drilling motor and pneumatic feeding means therefor, a main valve for controlling said motor and said feeding means, laterally extending operating means for said main valve, and supplemental means associated with said main valve for controlling said feeding means, said supplemental means having operating means therefor including a manually operable push button carried on the outer end of said main valve operating means.

5. In a drilling mechanism, a fluid actuated drilling motor, fluid actuated feeding means therefor, means including a throttle valve for controlling the fluid flow to said motor, an operating handle removably secured thereto, and means for controlling the pressure in said feeding means including a valve carried within and reciprocable longitudinally of said handle.
- 10 6. In a drilling mechanism, a motor, fluid pressure feeding means therefor, and means for controlling the fluid pressure supply thereto including an operating handle having a supporting portion for the hand of the operator projecting laterally relative thereto between its ends, and a supplemental feed controlling means including an operating push button carried by said handle adjacent said projecting portion.
- 15 7. In a drilling mechanism, a drilling motor, a pneumatic feeding means therefor, a main valve for controlling the fluid flow to said motor and feeding means, an operating handle therefor, said valve having a plurality of passages adapted to communicate respectively with said feeding means and a fluid pressure supply, said passages extending longitudinally through the valve to and communicating with passages in said handle, and means carried by said handle for controlling communication between said passages in the handle.
- 20 8. In a drilling mechanism, a drilling motor and pneumatic feeding means therefor, a main valve for controlling fluid flow to said motor and feeding means and having passages therein normally in communication with each other and with a fluid pressure supply and said feeding means respectively, a manually operable secondary valve for controlling communication between said passages having a seat in and adapted to close one of said passages and means including fine slots in the stem of said valve cooperating with the other passage for accurately regulating the fluid flow through said passages to the feeding means.
